UNITED STATES PATENT OFFICE.

AXEL HERMAN ANDERSSON, OF BENTON HARBOR, MICHIGAN, ASSIGNOR TO BAKER-VAWTER COMPANY, OF BENTON HARBOR, MICHIGAN, A CORPORATION OF MICHIGAN.

INTERLOCKING MECHANISM FOR FILING CASES AND THE LIKE.

Application filed October 18, 1923. Serial No. 669,368.

My invention relates to an interlocking device which in its broader aspect is applicable generally to any kind of structures having contiguous walls or other frame members. It is especially useful for locking together the units of various kinds of sectional sheet metal cabinets or cases and for the purpose of exposition is hereinafter particularly described as applied to sectional sheet metal filing cases or cabinets such as have come of recent years into extensive use in business offices. The object of my invention is the production of novel and improved interlocking mechanism suitable for the requirements in view which shall be of simple construction, easily manipulated to positively lock the sections tightly together, and in a high degree strong and secure, so that a stack of interlocked files shall in effect become a unitary structure.

With this purpose and the advantages mentioned in view I have invented and devised the interlocking device hereinafter described in detail, and my invention resides in the construction and arrangement of the cooperating members, the essential elements of the invention being more particularly pointed out in the appended claims.

In the accompanying drawing illustrating my invention as applied in a practical and preferred form to sheet metal filing receptacles, Figure 1 is a perspective of adjacent portions of two filing case sections, broken away, adjacent the locking devices to show the latter in locked position; Fig. 2 is a bottom plan view of one end of the upper filing case section, the lower one of the locking levers being shown in unlocked position and the upper in locked position; Figs. 3 and 4 side views showing different relative positions of the locking hooks and slots assumed by the parts in locking or unlocking the sections; and Fig. 5 a detail showing a forward hook locked.

The same reference characters indicate the same parts in all the figures of the drawing.

The top of the lower one of two filing case sections fitted to be interlocked through the use of my invention is equipped with a pair of oppositely arranged front locking hooks 1-1, and a pair of rear locking hooks 2-2 which are similarly directed, both front and

rear hooks in the present instance extending from their base or neck towards the front of the sections. For convenience of manufacturing, the rear hooks may be of the same shape as the front hooks, as shown. The lower wall of the upper filing case section to be interlocked with such lower section is formed with an inwardly extending horizontal flange or other frame member having opposite front slots 3-3 and rear slots 4-4 arranged to respectively receive the front and rear locking hooks above mentioned. The rear hooks 2 are formed each with a locking face 2^a arranged to hook forwardly over the wall in which the slot 4 is formed, the rear edge of the slot and the forward edge of the neck of the hook meeting when the two sections are in vertical alignment.

Adjacent the forward slots 3-3, on the top side of the horizontal frame member in which they are formed, are pivotally mounted a pair of locking levers 5-5 which swing in a horizontal plane and have locking faces arranged to latch under the locking faces 1^a-1^a formed on the front locking hooks, the shoulders 5^a at the outer or rear end of the latching portions of the lever being arranged to abut against a shoulder 1^b on the adjacent hook 1 at the rear end of the locking face 1^a. When the two sections are in vertical alignment the rear side of the hook 1^b (that is, the side opposite the forwardly projecting portion) abuts against the adjacent rearward end of the slot 3.

As shown, the tops of the front and rear hooks are rounded and cut away downwardly towards the rear so as to facilitate engagement of the hooks in their adjacent slots by sliding the top section rearwardly and downwardly while the front end of the unit is at first elevated very slightly so as to clear the front hooks, and then lowered by a direct transverse movement when the rear hooks have reached engaged position. When the two sections are in alignment the locking levers (which previous to the interlocking operation were in the transverse, disengaged position shown at the bottom of Fig. 2) are swung laterally into locked position, in which they stand longitudinally of the section, thus positively locking the upper section upon the front hooks of the

section below so as to prevent relative movement in any direction. The rear hooks lock the rear end of the sections against disengagement, and the latter can only be separated by manipulation of the locking levers, to permit the front end of the upper section to be first lifted, and then by a reverse sliding movement shifted forwardly in a manner the reverse of that above described.

10 Accidental disengagement is practically impossible as the locking levers are not in a position where they are liable to be accidentally moved and they are moreover mounted to have some frictional resistance to movement.

15 It will be understood that words indicating the position of the parts in the above description and in the claims are descriptive and used with reference to the ordinary 20 position of the filing sections particularly described, and that the position of the hooks and levers may be reversed, or my interlocking mechanism may be employed to lock sectional units side by side.

25 I claim:

1. Means for locking together a pair of filing sections or the like having contiguous walls, said means including a pair of simi-

larly directed hooks secured to a wall of one section, the contiguous wall of the other section being formed with a slot arranged to engage under one of said hooks by sliding movement and also with a slot arranged to receive the other hook by direct transverse movement when said first mentioned hook is 30 engaged, the rear side of said second-mentioned hook being arranged to abut against the adjacent rearward end of said second mentioned slot when such hook enters such slot, and a swinging latch carried by said 35 second-mentioned section arranged to latch laterally under said second-mentioned hook.

2. Latching means for securing together the walls of a pair of filing sections or the like, said means including a hook secured to one section and having a neck and a hook portion formed with a shoulder on its under side, and a swinging latch on the other portion arranged to latch under the terminal portion of said hook and abut against said shoulder thereon, said other section being slotted to receive said hook and the rear side of said hook being arranged to abut against the adjacent rearward end of said slot when the latch is engaged.

AXEL HERMAN ANDERSSON.
